UNITED STATES PATENT OFFICE.

JACOB BLAKE, OF BEDFORD, IOWA.

BURIAL-CASKET.

No. 813,942.

Specification of Letters Patent.

Patented Feb. 27, 1906.

Application filed November 7, 1905. Serial No. 286,238.

To all whom it may concern:

Be it known that I, JACOB BLAKE, a citizen of the United States of America, residing at Bedford, in the county of Taylor and State of Iowa, have invented new and useful Improvements in a Combined Bier and Burial-Casket, of which the following is a specification.

This invention relates to improvements in burial apparatus, and contemplates particularly improvements in that class of burial apparatus embodying an inclosing casing of a portable design and a body-receptacle adapted to be placed therein and deposited there-
15 with in the grave.

The object of the invention, generally stated, is to provide burial means wherein the body may be laid before and during the burial ceremonies in a light coffin which may be
20 readily transported and which is adapted to be inclosed in a box or casing which may be contained in the hearse during such ceremony and in which the body when transported to the hearse is inclosed and hermetically
25 sealed for burial, such construction of the burial means obviating the necessity of using caskets of cumbersome construction and which are difficult to handle.

Another object of the invention is to provide an exterior coffin box or casing of simple construction which may be inexpensively manufactured and is adapted to be readily and conveniently hermetically sealed to prevent the access of air and moisture.

Still another object is to provide a coffin which will hold the body securely against displacement, which may be fastened in position within the casing, and which embodies certain improved features of construction
40 hereinafter described.

In the accompanying drawings, Figure 1 is a side elevation of the exterior coffin box or casing. Fig. 2 is a longitudinal section of the same, showing in side elevation the coffin disposed therein. Fig. 3 is a horizontal section on the line 3 3 of Fig. 2. Fig. 4 is a vertical transverse section on the line 4 4 of Fig. 2.

Referring now more particularly to the drawings, the numeral 1 designates the exterior coffin box or casing, and 2 the coffin proper or body-receptacle. The casing is made in practice of metal or any other suitable air and water tight material and is composed of a bottom 3, sides 4, a top wall 5, and an end wall 6, forming a body permanently

sealed or closed at one end and free from joints through which air and moisture may gain access to the interior thereof. At its closed end the casing has a flange or extension 7 extending across the base and upon the sides thereof and strengthening the casing-body at that point, the base portion of said flange serving as a supporting-leg 8 to hold the casing at a suitable elevation. The interior of the casing is strengthened by braces 9, extending across the top and bottom and up along the sides thereof, each brace being in the form of a ring conforming to the cross-sectional contour of the casing and secured thereto in any suitable manner. These braces reinforce the top and side walls to prevent their displacement under the weight of the earth resting thereon when the casing is deposited in the grave.

The coffin or body-receptacle 2 is adapted to be inserted into the casing through the other or open end, which open end is closed and hermetically sealed after the insertion of the occupied bier by a head 10. This head 30 10 is provided with an inwardly-extending flange 11, while the end of the casing is formed with a surrounding flange 12 and a hood-flange 14, and between these flanges a gasket or packing-ring 14, of rubber or other suitable material, is applied and clamped to form an absolutely air and water tight joint. Bolts or other suitable fastenings 15 extend through the gasket and flanges and firmly secure the head or closure in applied position. 90 The lower portion of the flange 12 extends below the bottom wall 3 and performs the function, in connection with the lower portion of the head, of a supporting-leg co-operating with the leg 8 to hold the casing elevated.

Bracing-straps 16, extending beneath the bottom and part way up along the sides of the casing, are formed thereon or suitably secured thereto and serve as supports for handle-rods 17.

The hood-flange 13 forms an extension of the top wall 5 and extends beyond the upper cross portion of the flange 12 and over the upper edges of the gasket and head 10, and thus shields the top part of the joint to prevent any possible trickling of water by gravity between the members of the joint.

The coffin 2 may be formed of any suitable material and is provided on its sides with handles 18 and upon its under side with rollers 19, whereby it may be readily introduced into the casing. It is also provided in its

top with a glass panel 20, carried by a suitable form of lid 21, which may be fastened in position in any preferred manner after the insertion of the body. The panel 21 may 5 consist of a single piece of glass or other transparent material or of a series of glass sections, as preferred, and I have not deemed it necessary to show any unimportant details of variation of this character, as they constitute no part of my invention. The head end 10 of the coffin is provided with a suitable handle 22 to facilitate its insertion and removal, and above the center of the panel 20 is arranged a rod 23, suitably fixed to the ends of the coffin and serving as a support for an ornamental curtain or piece of drapery 24, which has a central loop embracing the rod in such manner that the curtain may be 15 drawn over the top of the coffin to entirely cover the panel or adjusted thereon to fully 20 or partly expose the same and the body therethrough.

On the under side of the coffin are arranged 25 apertured eyes or brackets 25, adapted to engage a fastening-rod 26, secured at one end to the front wall of the casing, as indicated at 26', and adapted to be engaged at its opposite end by a hinged or pivoted clamp or fastener 27, adapted to be fixed to the bottom 30 wall 3 of the casing by a suitable clamping-screw 28. This fastener is thrown out of engagement with the rod when the coffin is to be inserted into the casing, so that when the coffin is slid into the casing the rod will pass 35 through the eyes 25, thus fastening the coffin firmly in position, after which the fastener 27 is turned down and secured to hold the rod from independent movement and prevent shifting of the coffin thereon. Thus the coffin 40 will be held from shifting in the casing while the same is being transported and lowered into the grave.

It will be understood that the coffin 2 is 45 used as a receptacle for the body up to the time when it is to be transported by a hearse and that the casing fits into the hearse and need not be carried into the residence or other place where the body is kept before the funeral. After the funeral ceremonies at the 50 residence have been performed the coffin is carried out by the pall-bearers in the usual way and inserted into the casing in the hearse and the casing then sealed. If the funeral is held at the church, the casing, with the 55 closed coffin, may be carried into the church upon a funeral-car and the coffin removed therefrom during the ceremonies. By the construction described the access of air and moisture to the body inclosure will be prevented 60 for an indefinite period, and the necessity of handling a heavy coffin or casket of the ordinary type in transporting the body

from a residence to a hearse will be avoided, thus preventing to a large extent overturning of the casket and other accidents of like 65 character which happen during the transportation of heavy and unwieldy coffins.

Having thus described the invention, what is claimed as new is—

1. In a burial device, a receptacle having a 70 transparent panel, a rod disposed longitudinally thereof above said panel, and a curtain longitudinally adjustable on said rod to expose or cover the panel.

2. In a burial apparatus, an exterior coffin 75 box or casing comprising a body provided at one end with a strengthening-flange depending to form a supporting-leg and having its opposite end open and formed with a surrounding flange and a hood projecting beyond the 80 upper portion of the flange, said flange having a depending portion constituting a complementary leg, a head for closing the said open end of the casing provided with an inwardly-extending flange, a gasket interposed 85 between the body and head flanges and said body-flange and marginal portion of the head outside the flange thereon, and bolts passing through the body-flange, gasket and marginal portion of the head and tightly joining said 90 parts, the hood lapping over the upper portion of the joint, substantially as described.

3. In a burial apparatus, a casing, a coffin 95 adapted to be inserted longitudinally therein, a rod permanently fastened at one end within the casing and having its opposite end free; perforated members on the coffin adapted to engage and slide along the rod upon the insertion of the coffin, to connect the coffin and casing together, and means for fixing the free 100 end of the rod to the casing.

4. In a burial apparatus, a casing, a coffin adapted to be inserted longitudinally therein, interengaging devices upon the casing and coffin brought into engagement when the latter is inserted to hold the same stationary 105 within the casing, and means for maintaining the parts in connected relation.

5. In a burial apparatus, a casing having 110 an opening at one end thereof, a rod fixed at one end within the casing, a coffin adapted to be inserted longitudinally into the casing and provided with members to engage and interlock with said rod as the casket is inserted, a fastening device upon the casing to 115 engage and hold the free end of the rod from movement, and a closure for the casket-opening.

In testimony whereof I affix my signature in presence of two witnesses.

JACOB BLAKE.
